DESCRIPTION

U.S. PATENT DOCUMENTS

FIG. 1 is a perspective view showing the new design for a
respirator mask having a circular button;

FIG. 2 is a front view thereof;

FIG. 3 is a rear view thereof;

FIG. 4 is a right side view thereof, the left side being a mirror
image thereof;

FIG. 5 is a top view thereof; and,

FIG. 6 is a bottom view thereof.

The broken lines in the drawings illustrate portions of the
respirator mask having a circular button which form no part of
the claimed design.
